(57) CLAIM

I claim the ornamental design for a locking treat disc set, as shown and described.

DESCRIPTION

FIG. 1 is a front, top and right side perspective view of a locking treat disc set, according to my new design;

FIG. 2 is a front elevation view thereof;

FIG. 3 is a back elevation view thereof;

FIG. 4 is a right side elevation view thereof; and,

FIG. 5 is a left side elevation view thereof.
